SPEED CONTROL MECHANISM FOR
GRINDING MACHINESHerbert A. Silven, Worcester, Mass., assignor to
Norton Company, Worcester, Mass., a corpora-
tion of Massachusetts

Application November 29, 1932, Serial No. 644,873

4 Claims. (Cl. 51—166)

This invention relates to grinding machines, and more particularly to a mechanism for automatically controlling the rotative speed of a grinding wheel so as to maintain a substantially constant peripheral speed as the diameter of the wheel decreases due to wear.

In cylindrical grinding machines which have been heretofore produced and sold on the market, it has been customary to provide either a belt or a motor drive for the grinding wheel. The wheel spindle is either driven at a single speed during the entire life of the wheel or, in some cases, a two-stepped cone pulley has been provided so that after the wheel had worn away to a predetermined extent, the operator might increase the speed (R. P. M.) so as to more nearly approach the correct peripheral speed of the wheel.

In grinding practice today, it is customary for a grinding wheel to be sold with a definite recommended speed of rotation. If the customer desired to obtain the maximum cutting efficiency for the wheel purchased, it must be rotated at the recommended speed. As the grinding operation proceeds, the grinding wheel wears away during use or is trued away periodically to recondition the surface, each of which reduce the diameter of the wheel. As the grinding wheel wears away, its diameter and its peripheral speed decrease so that the cutting efficiency of the wheel is continually being decreased. In production grinding in large manufacturing plants, it is common practice to utilize a wheel only until it has worn away to a given extent and then to either discard the remainder of the wheel or to have another machine upon which the wheel which is reduced beyond efficient use on the first machine may be utilized. The speed of rotation of the second machine is increased so that the peripheral speed of the worn wheel, which has been changed to the second machine, will be substantially equal to the peripheral speed of the original wheel when mounted on the first machine. By having several batteries of machines: the first battery of machines, for example, taking a 36" diameter wheel and wearing it down to 32", and then a second battery to take the 32" wheel and wear it away to 28", it is possible to use up the grinding wheel to the maximum extent, without undue loss of efficiency. Even with such a practice, the maximum efficiency is not obtained, due to loss of time during wheel changes and also due to the fact that while in use on a given battery of machines, the peripheral speed of the grinding

wheel does not remain constant as it wears away.

To obtain the maximum efficiency of the wheel, it is desirable to provide a suitable speed control mechanism which will maintain a substantially constant peripheral speed of the grinding wheel during its entire life. By utilizing such a mechanism for maintaining a constant peripheral speed, it is possible to utilize the entire useful part of a grinding wheel, without the necessity of changing the wheel from one battery of machines to another after it has worn away to a predetermined extent.

It is the primary object of this invention to provide a suitable driving and speed controlling mechanism for rotating a grinding wheel, which is automatically actuated as the wheel wears away to increase the speed of rotation of the wheel so as to maintain a substantially constant peripheral speed thereof.

It is another object of this invention to provide a suitable means, which is controlled by movement of the slide supporting either the grinding wheel or the work piece, which automatically actuates a speed control device to advance the speed of rotation of the wheel as it wears away.

It is a further object of this invention to provide a grinding machine with a means controlled by movement of the work or wheel slide so as to prevent the wheel from being rotated at other than a predetermined speed, but which allows the wheel to rotate at a higher speed as it decreases in size.

It is a still further object of this invention to provide a speed regulating device for the grinding wheel which automatically reduces the rotative speed of grinding wheel speed before a new full-sized wheel may be mounted on the machine.

Other objects will be apparent from the following disclosure. As shown in the drawing, one embodiment of the invention has been illustrated in which like reference numerals indicate like parts:

Fig. 1 is a side elevation of a grinding machine, showing the arrangement of the grinding wheel, the work support and the motor drive for the grinding wheel and diagrammatically illustrating the wiring diagram for the speed control of the electric motor.

Fig. 2 is a fragmentary cross-sectional view on an enlarged scale, taken approximately on the line 2—2 of Fig. 1, showing the lost motion driving connection between the movable slide and the speed controlling rheostat;

Fig. 3 is a fragmentary cross-sectional view, taken approximately on the line 3—3 of Fig. 2; and

Fig. 4 is a fragmentary view, showing the improved speed controlling mechanism applied to a cylindrical grinding machine, in which the wheel is fed toward and from the work support.

This invention involves a grinding machine having a work support, a rotatable grinding wheel and a support for moving one of said members towards and from a finish grinding position. The machine includes a means controlled by movement of the support to the finish grinding position which automatically controls the maximum speed of rotation of the grinding wheel. In the preferred construction, the grinding wheel is rotated by an electric motor of the variable speed type, and a suitable speed controlling rheostat is connected to regulate the speed of rotation of the motor. The movement of the rheostat control lever is automatically actuated by transverse movement of the slide so that as the grinding wheel is worn away, the rotative speed of the wheel is increased automatically so as to maintain a substantially constant peripheral speed of the grinding wheel during its entire life. The actuating mechanism for the speed controlling rheostat is preferably provided with a suitable lost motion connection, which permits the separation of the wheel and work through a distance normally required when separating the wheel and work to remove the finish ground piece of work and replace it with a new piece, without moving the speed controlling rheostat. The actuating mechanism and speed controlling device are so arranged that when the grinding wheel is worn away and must be replaced, the separating movement between the wheel and work to make room for a full-sized grinding wheel automatically turns the rheostat in the reverse direction so that when the new, full-sized grinding wheel is mounted in place, it will be rotated at the proper speed.

As illustrated in the drawing, a grinding machine is provided having a base 10 supporting a rotatable grinding wheel 11 in suitable bearings 12 which are integrally supported on projections 13 of the base 10. An electric motor 14 is fixedly mounted on the base 10 and is connected by a driving belt 15 to rotate the grinding wheel 16.

A work supporting carriage 18 is mounted for a transverse movement on slideways 19 and 20 on the base 10. The work slide may be fed transversely by any suitable feeding mechanism which, as shown in Fig. 1, may comprise a half nut 23 depending from the slide 18 and meshing with a feed screw 21 which is journalled in suitable bearings (not shown) in the base 10. The outer end of the feed screw is provided with a hand wheel 22 so that the operator may manually rotate the screw and feed the work slide toward and from the grinding wheel.

A cylindrical work piece 25 is rotatably mounted on centers on the headstock (not shown) and a footstock 26 which are mounted on a longitudinally movable work carriage 27. The carriage 27 is mounted to slide on a V-way 28 and a flat way 29 on the transversely movable work carriage 18, and is provided with a rack 30 which meshes with a gear 31. The gear 31 is mounted on the end of a shaft 32 which is suitably journalled in bearings (not shown) in the work slide 18. The outer end of the shaft 32 is provided with a manually operable hand wheel 33 so that the operator may traverse the work carriage

longitudinally of the machine to position the work relative to the grinding wheel or may cause the necessary relative reciprocation between the wheel and work during grinding, if desired. This longitudinal movement of the work relative to the grinding wheel may be accomplished by means of any of the well-known power driven reciprocating mechanisms but for the sake of simplicity of illustration, a manual adjustment for the carriage has been shown.

The grinding wheel rotating motor 14 is preferably of a variable speed type which is connected to a suitable source of power, as diagrammatically indicated by the power lines 35 and 36 which are connected through a rheostat 37 to regulate the speed of rotation of the motor 14.

In order to attain the primary object of this invention, a suitable mechanism is provided for actuating the rheostat control arm 38 automatically to increase the rotative speed of the grinding wheel 11 as it wears away so as to maintain a substantially constant peripheral speed of the wheel during its entire useful life. The movable slide is preferably provided with a rack bar 39, mounted on the lower side of the slide 18, meshing with a gear 40 which is rotatably mounted on a stud 41 which is fixedly mounted on the base 10. A sprocket 45 is also rotatably mounted on the stud 41 and is connected by a link chain 46 to a sprocket 47 on the rheostat shaft 48. It will be readily appreciated that transverse movement of the slide 18 will operate through the rack 39, gear 40, sprocket 45, chain 46, sprocket 47 and shaft 48 to rotate the control arm 38 of the rheostat 37, so as to vary the speed of the motor 14.

The gear 40 and the sprocket 45 may be integrally connected so that any movement of the transverse slide 18 will be transmitted to the rheostat 37. In the preferred form, however, it is desirable to provide a suitable lost motion connection between the gear 40 and the sprocket 45 which, as illustrated, comprises a pin 50 integral with and projecting from the gear 40. The pin 50 rides in a cut-out portion 51 (Fig. 3) in the hub 52 of sprocket 45. The length of the cut-out portion of the gear 45 is sufficient to allow normal separation of the wheel and work after finish grinding one piece of work to enable the operator to remove the finish ground work and to replace it with a new piece without disturbing or changing the speed of the wheel. As the operator feeds the work piece 25 toward the wheel by moving the slide 18, the rack 39 causes a rotation of the gear 40 and pin 50 in a counterclockwise direction, as indicated in Fig. 1. There is sufficient movement in the cut-out portion 51 so that when the work is ground to size, the pin 50 will contact with the end 51 of the cut-out portion. As the grinding wheel wears away due either to normal grinding action or truing, the work slide will of necessity advance further in a forward direction toward the wheel spindle 16 in order to finish grind and reduce the work to the predetermined size. This further feeding movement transmits a rotary motion through the pin 50, hub 52, sprocket 45, and chain 46 to rotate the rheostat control arm or thereby automatically increase the speed of the motor 14 and also the peripheral speed of the wheel 11. The rheostat is preferably so constructed and so connected through the gear and rack that the advancing movement of the work slide toward the wheel as the wheel wears away is sufficient to advance the rotative speed of the motor 14 so as

to maintain a constant, uniform peripheral speed of the wheel during its entire useful life.

In order that the initial rotative speed of the grinding wheel may be set according to the specific requirements of the grinding operation, the sprocket 45 is mounted on a reduced portion 55 of the hub 52. A screw threaded collar 56, which is threaded onto an extending portion of the hub 52, serves to lock the sprocket 45 in a fixed relation with the hub 52. By loosening the threaded collar 56 and rotating the sprocket 45, the sprocket 47 controlling the rheostat may be adjusted to the desired extent to regulate the speed of the motor so as to rotate the grinding wheel at the desired rate. The operator then locks the collar 56 to maintain the sprocket in a fixed relation with the hub 52. The operation of the machine as the wheel wears away will then automatically advance the rotative speed of the wheel as the wheel wears away and the work approaches nearer the axis of the wheel on successive grinding operations to maintain a substantially constant and uniform peripheral speed of the wheel.

This speed controlling apparatus is equally adapted for use in a plain cylindrical grinding machine of the type in which the grinding wheel is rotatably supported on a transversely movable wheel slide. Such a machine may comprise a base 10 (Fig. 4) supporting a rotatable wheel 11 which is mounted in suitable bearings 60 on a transversely movable wheel slide 61. The grinding wheel 11 is rotated by a variable speed electric motor 62 which is mounted on the wheel slide 61 and connected by means of a belt 63 to rotate a wheel spindle 64. A work supporting table 65 is slidably mounted on V-way 66 and flat way 67 of the base 10 and is arranged for longitudinal movement by a manually operable wheel 68 which is carried by the shaft 69. The shaft 69 carries a gear 70 meshing with a rack 71 depending from the work slide 65.

The wheel slide may be fed toward and from the work piece by any of the well-known feeding mechanisms but for the sake of simplicity of illustration, a manually operable mechanism has been illustrated, comprising a manually operable feed wheel 77 mounted on a rotatable shaft 72. The shaft 72 carries a gear 13 meshing with a gear 14 on the front end of a feed screw 75 which is rotatably supported in bearings (not shown) in the base 10. The feed screw 75 engages a half nut 76 depending from the wheel slide 61. The speed controlling unit for regulating the speed of the electric motor 62 is actuated by a rack 78 on the wheel slide. The rheostat and the controlling mechanism therefor are identical with the illustration as shown in Fig. 1. Consequently, the mechanism is not described in detail in connection with Fig. 4. The parts for the speed control are numbered to correspond with the similar parts previously illustrated and described in Figs. 1, 2, and 3.

The operation of this machine is readily apparent from the foregoing disclosure. The operator mounts a full-size abrasive wheel on the wheel spindle. The nut 56 is then loosened and the sprocket 45 rotated to adjust the rheostat so as to rotate the wheel at the desired speed. The grinding operation may then be started and, as previously explained, the lost motion connection in the gearing allows normal separation of the work and wheel without changing the speed of the wheel. As the wheel wears away due to normal wear or truing, the movable slide advances a greater distance towards the axis of the sta-

tionary member in grinding the work piece to a finished size. This further movement of the slide operates through the lost motion gearing to automatically advance the rheostat to increase the rotative speed of the wheel so as to maintain a substantially constant peripheral speed of the wheel as it wears away.

Having thus described the invention, what is claimed as new and desired to secure by Letters Patent is:

1. A grinding machine comprising a base having a rotatable work support and a rotatable grinding wheel thereon, means including a variable speed electric motor to rotate said wheel, means including a rheostat to regulate the feed of said motor, a transversely movable slide carrying either the work support or the grinding wheel for movement relatively toward and from each other, a feeding mechanism to feed said slide and cause a relative approaching and receding movement between the work support and wheel to grind successive work pieces to a predetermined size, driving connections between said slide and rheostat which are arranged so that movement of the slide to cause a relative approaching movement between the wheel and work support automatically actuates said rheostat during grinding to maintain a substantially constant peripheral speed of the wheel as it wears away, and a lost motion device in said driving connections whereby the normal transverse feeding movement between the wheel and work support during grinding does not affect said rheostat speed regulating means.

2. A cylindrical grinding machine comprising a base having a rotatable work support and a rotatable grinding wheel thereon, means including a variable speed electric motor to rotate said wheel, means including a rheostat to regulate the speed of said motor, a transversely movable slide carrying either the work or the grinding wheel for movement relatively toward and from each other, a feeding mechanism to feed the slide and cause a relative approaching and receding movement between the work support and the wheel to grind successive work pieces to a predetermined size, and lost motion connections between the slide and rheostat which are arranged so that movement of the slide to cause a relative approaching movement between the wheel and work support automatically actuates said rheostat during grinding to maintain a substantially constant peripheral speed of the wheel as it wears away, the lost motion of said gearing providing means whereby the normal transverse feeding movement between the grinding wheel and work support during grinding does not affect said rheostat speed regulating means.

3. A cylindrical grinding machine comprising a base having a rotatable work support and a rotatable grinding wheel thereon, means including a variable speed electric motor to rotate said wheel, means including a rheostat to regulate the speed of said motor, a transversely movable slide carrying either the work support or the grinding wheel for movement relatively toward and from each other, a feeding mechanism to feed said slide and cause a relative approaching and receding movement between the work support and wheel to grind successive work pieces to a desired size, a rack carried by said slide, a lost motion gearing connecting said rack with the rheostat which is arranged so that movement of said slide to cause a relative approaching movement between the wheel and work support auto-

5 matically actuates said rheostat during grinding to maintain a substantially constant peripheral speed of the wheel as it wears away, the lost motion of said gearing providing means whereby
5 the normal traverse feeding movement between the grinding wheel and work support during grinding does not affect the said rheostat speed regulating means.

4. A grinding machine comprising a base having a work support and a rotatable grinding wheel thereon, means including a variable speed electric motor to rotate said wheel, means including a rheostat to regulate the speed of said motor, a transversely movable slide carrying 10 either the work support or the grinding wheel for movement relatively toward and from each other, a feeding mechanism to move said slide
15

transversely and cause a relative approaching and receding movement between the work support and the grinding wheel to grind successive work pieces to a desired size, a rack bar carried by said slide, a rotatable gear meshing with said rack, a stud on said base for supporting said gear, a sprocket rotatably mounted on said stud, a lost motion connection between said gear and sprocket, and a link chain connecting the sprocket with the rheostat to actuate the latter 10 during grinding so as to automatically maintain a substantially constant peripheral speed of the wheel during grinding as it wears away but permit normal movement of the slide towards and from the work without affecting the wheel speed. 15
